(57) **CLAIM**

The ornamental design for a body blade, as shown and described in the accompanying drawings.

DESCRIPTION

FIG. 1 is a perspective view of a body blade, showing our new design.

FIG. 2 a front elevation thereof;

FIG. 3 is a rear elevation view thereof;

FIG. 4 is a side elevation view thereof;

FIG. 5 is a side elevation view of the opposite side view shown in FIG. 4;

FIG. 6 is a top plan view thereof; and,

FIG. 7 is a bottom plan view thereof.

The broken line showing of the environment is for illustrative purposes only and forms no part of the claimed design.
